FEED MECHANISM FOR ROLLER TOWEL CABINETS

Ramiel Morris, St. Louis, Mo.

Application July 11, 1947, Serial No. 760,317

9 Claims. (Cl. 312—38)

1

This invention relates to improvements in feed mechanism for roller towel cabinets.

An object of the invention is to provide for use in a roller towel cabinet a feed mechanism whereby selected lengths of toweling may be withdrawn from a roll of toweling and positioned accessible for use, together with means for latching the feed mechanism when a selected length of toweling has been withdrawn, and which, upon cessation of tension on the toweling, automatically unlatches the mechanism in order that a successive unused length of toweling may be brought into position for use solely by successive pulls and release of tension on the toweling.

Another object of the invention is to provide improved mechanism of the type designated, whereby the soiled toweling may be easily removed and the mechanism reloaded with a clean length of toweling.

Another object of the invention is to provide improved means for guiding the feed movement of the toweling through the mechanism, whereby the toweling will be fed evenly and uniformly to present successive, smooth areas of the toweling for use.

Another object of the invention is to provide, in a mechanism of the type mentioned, improved roller supports for the length of toweling which will operate with minimum wear on the toweling during the feed operation.

Another object of the invention is to provide mechanism of the type stated, which may be economically manufactured, assembled and disassembled, and which will be efficient and durable in use.

Additional advantages of the invention will appear from the following detailed description thereof taken in connection with the accompanying drawings, in which:

Fig. 1 is a front view of the upper part of the towel cabinet, parts being shown dotted, to illustrate the feed mechanism embodied therein;

Fig. 2 is a rear view of the parts shown in Fig. 1;

Fig. 3 is a left end elevation, as viewed in Fig. 1, parts being shown dotted, of the operating head of the towel cabinet;

Fig. 4 is a right end elevation, as viewed in Fig. 1;

Fig. 5 is a vertical section taken substantially on the line 5—5 of Fig. 1;

Fig. 6 is a vertical section taken substantially on the line 6—6 of Fig. 1;

Fig. 7 is a vertical section taken substantially on the line 7—7 of Fig. 1;

2

Fig. 8 is an enlarged fragmentary view of the latching and unlatching mechanism at the point in the cycle before it enters latched position and the position that the parts assume at the end of the feed of the selected length of toweling;

Fig. 9 is a similar view to Fig. 8, with the latching and unlatching mechanism shown after release of the tension on the towel length, and at the beginning of the first phase of the feed of a successive length of toweling;

Fig. 10 is a view illustrating the parts advanced towards a resetting of the latching mechanism during intermediate feed of the length of toweling;

Fig. 11 is a similar view illustrating the parts further advanced and during the final phase of the feed of the selected length of toweling;

Fig. 12 is a vertical sectional view taken substantially on the line 12—12 of Fig. 11;

Fig. 13 is a sectional view taken substantially on the line 13—13 of Fig. 11; and

Fig. 14 is a sectional view taken substantially on the line 14—14 of Fig. 13.

In the embodiment of the invention selected for illustration, the frame of the cabinet is shown as including side standards or supports 10, which may be extended downwardly and carried by a base (not shown), so that the operating head of the cabinet may be supported at an elevation, and the cabinet, as a whole, may be portable. There is a table 11 formed with front and back flanges 12 bevelled on their inner faces and supported transversely between the standards 10 and at the top thereof. The table 11 is adapted

30 to support the roll of clean toweling, and the flanges 12 serve to prevent the roll from displacement from its support by preventing it from rolling over the edges thereof.

The operating head of the cabinet is supported at an elevation above the table 11 by rectangular members 13 extending transversely of each end of the table 11.

The case of the head of the cabinet which supports the feed mechanism comprises a pair of end plates 14 and 15 carried by the top edge of the members 13 at each side of the machine, respectively.

At the back of the case, there is a transverse plate 16 flanged at each end and supported between the inner faces of the plates 14 and 15. The upper end of the plate 16 has an inwardly upwardly inclined flange 17, which constitutes a guide for the toweling as it moves to the winding roll for the soiled toweling, as will be later described.

At the front of the case is a flanged inwardly inclined plate 18, which serves as a guide for the toweling wound on the winding roll.

The construction of the feed mechanism may be best understood by describing the parts in the sequence of the movement of the fresh roll of toweling through the mechanism.

A roll of clean toweling is placed loosely on the table 11 and is prevented from rolling out of position by the flanges 12. The free end of the toweling is passed between a friction surfaced roller 20 and a guide roller bar 21.

The roller 20, having reduced cylindrical extensions 23 and 24 forming trunnions, is rotatably mounted in bearings 25 and 26, respectively, in the plates 14 and 15. The member 24 extends through its bearing to the exterior of the plate 15 and has a pinion 27 secured thereto at its extremity.

Reduced extremities of the roller bar 21 extend through laterally aligned curved slots 30 and 31 located, respectively, in the plates 14 and 15. The roller bar 21 is therefore mounted so that it may be moved toward and away from the roller 20 as the reduced extensions of said bar are moved downwardly or upwardly in the slots 30 and 31. Provision is thereby made for opening the space between the roller 20 and the roller bar 21 in order that the free end of the toweling may be easily passed around the roller 20, the toweling first extending rearwardly of the roller and then being carried over the top thereof. A section of the toweling hangs freely from the upper front segment of the roller 20. After the free end of the toweling has been thus positioned, the roller bar 21 is moved to a position adjacent to the underface of the roller 20 and thereby maintains the toweling in frictional contact with said roller substantially around the entire periphery thereof.

The roller bar 21 is so mounted and latched as to maintain this operative adjustment after the toweling has been passed over the roller 20.

The means for latching the roller bar 21 and of permitting its release when the cabinet is loaded comprises a pair of links 33, one being pivotally connected to each of the respective extremities of the member 21. For this purpose, each end of the roller bar 21 has a reduced portion that fits through an opening formed on the forward end of each link 33. The links are located against the inner faces of the side plates 14 and 15 adjacent to the slots 30 and 31, respectively. The inner ends of the links are pivoted, respectively, to forwardly extending arms of a bail 34, the bail 34 being U-shaped and dimensioned so that its forwardly extending arms may align with the links 33. The connection between the arms and the links is by pivot pins 35. The arms of the bail 34 are pivoted at 36 to the inner faces of the plates 13 and 14. At the right side of the cabinet a latch pawl 37 is supported upon the inner face of the plate 14 on a pivot pin 38 which extends through the plate to the exterior face thereof. On the outer extremity of the pin 38 there is attached a finger piece 39 so that, by manipulation of the finger piece, the pawl may be rocked rearwardly from a vertical position, which it assumes by gravity, to an angular position raised from the upper edge of the link and bail arm. The pawl 37 has an inwardly extending flange 40 at its lower extremity which overlies the upper edge of the link and bail at the point of its pivot connection when said parts are extended and lie substantially horizontal, as

illustrated, for example, in Fig. 7. Horizontally disposed abutment pins 41 limit the downward movement of the linkage. The pawl, therefore, provides a latch device for holding the roller bar 21 in operative position adjacent to the roller 20.

When the pin 38 is rocked by manipulation of the finger piece 39, the toggle connection between the links and the bail arm may be retracted, permitting the extremities of said roller bar to ride upwardly in the curved slots 30 and 31 to open the space between the roller 20 and the roller bar 21, providing free access for mounting the toweling over the roller 20 when the cabinet is being loaded with a fresh roll of toweling.

When the roller bar 21 is in operative adjustment, it serves as a pressure bar to insure uniform contact of the toweling with the roller 20 across the face thereof and thus maintains a smooth and even feed of the successive lengths of toweling.

After the toweling has been mounted over the roller 20, as described, it is extended downwardly in the space between said roller and toward the base of the cabinet, and is then looped upwardly toward the back of the cabinet. The front and back of the loop hang substantially vertically since they are guided against the relatively wide table 11 with its flanges at its front and back edge. The length of the toweling at the front of the loop is of sufficient dimension laterally and longitudinally to provide sufficient towel surface for each individual use.

The upper end of the back of the loop rides over the outer face of the plate 16 and of the forwardly inclined flange 17, and is kept in lateral alignment by a pair of inwardly directed L-shaped flanges 42 at each side of the flange plate 16. Another pair of similar flanges may be located at each side of the inclined flange 17, if desired.

After passing over the edge of the flange 17, the toweling is carried forward and is wound on a winding roll 43, being directed forwardly over the front face of the roll and over the top face of a friction roller 44.

In order to maintain a smooth feed of the length of toweling as it comes over the guide plate 16 and flange 17, a roller bar 45 is mounted in forwardly curved slots 46 and 47 formed in the side plates 14 and 15, respectively. The roller bar 45 is free to move in these slots, and when it rests in the bottoms thereof the roller is substantially parallel with the face of the flange plates 16-17 at the point the flange 17 curves inwardly. The roller bar 45 bears, due to its weight, transversely across the surface of the toweling moving to the winding roll, and thereby holds its edges aligned and its surface smooth so that it will be wound evenly on the roller.

The winding roller 43 has trunnions 48 at each end, which trunnions ride in substantially vertical slots 49 so that, as the soiled toweling is rolled on the winding roller, the roller will rise in the slots. Therefore, the lower surface of the roll B of the soiled toweling will always be adjacent to the upper face of the roller 44.

The roller 44 is, in fact, a feed roll as it is rotated by a power transmission connection with the roller 20.

The roller 44 is journaled in bearings in the side plates 14 and 15, respectively. At the left of the mechanism, there is a reduced extension 50 of the roller 44, which extension extends

through the plate 15 and has a pinion 51 keyed or otherwise secured thereto.

At the opposite extremity of the roller 44, a bearing assembly is provided which rotatably supports the roller 44 at that end. The bearing assembly is of a design that is easily detachable and the details of which are particularly illustrated in Figs. 13 and 14.

This construction includes a metal socket 52 set into the end face of the roller 44. This socket has a recess with flattened sides and curved top and bottom with a reduced similar recess at its inner end, as will clearly appear from these views of the drawings.

A short stud shaft 53 has a flattened section 54 and a reduced flattened inner extremity 55. This member fits into the socket and rotates with the roller 44 in operation, but may be readily removed from the socket. This device, therefore, permits the roller 44 to be easily dismounted when the soiled roll of toweling is to be removed and the cabinet is to be reloaded and the feed mechanism set up for feeding a clean roll of toweling.

The outer extremity of the stud shaft 53 extends through a bushing 56 in the plate 14 and has attached thereto an arm 57 which is an element of the latching and unlatching mechanism, as will be later explained.

It will be remembered from the previous description that, as successive lengths of toweling are withdrawn from the clean roll A of the toweling by exerting pull in the direction of the arrow a (Fig. 5), the roller 20 rotates in the direction indicated by the arrow b. As long as pull is exerted, the roller 20 rotates and its rotary movement is imparted to the roller 44 through a chain link connection 60 operating over the pinion 27 and the pinion 51 mounted, respectively, on the extremity of the roller 20 and the roller 44.

The latching and unlatching of the feed mechanism is accomplished as a result of locking and unlocking the roller 44 for and against rotation. Because of the positive link chain connection 60 between the roller 44 and the roller 20, when the former is locked, the latter will likewise be locked preventing further withdrawal of the length of toweling until the mechanism is unlocked. As the surface of the roller 20 is a friction surface, unless the roller 20 is in adjustment to revolve, the contact of the inner face of the toweling with the roller 20 will prevent any further downward movement of the toweling when the roller 20 is held against rotation.

The mechanism for accomplishing this purpose includes a detent device comprising plates 61 and 62. The plate 61 is mounted for rocking action on a stud shaft 63 extending outwardly from the outer face of the side plate 14, as shown particularly in Fig. 12. This plate has a lower inwardly extending arm 64 generally rectangular in shape and located near the bottom of the plate. At the top of the plate is a projection 65 having a downwardly sloping top wall and an upwardly projecting extension 66. Between the opposing top edge of the extension 64 and the bottom edge of the extension 65 is a substantially U-shaped space of a substantial depth. The plate 61 is provided with a tail piece in the form of a hook 67 and a coiled spring 68 is connected over the tail piece 67 at one end and is attached at its lower end to a pin 69 supported by the plate 14. The tendency of the spring is to urge the plate 61 to rock in a counterclockwise direction.

The plate 62 is mounted for rocking movement on a stud shaft 70 positioned above and extend-

ing outwardly from the plate 14. The plate 62 is supported on a plane inwardly of the inner face of the plate 61 so that the plates rock in parallel adjacent planes. The plate 62 has, on its bottom edge, an integral lug 71 that extends outwardly at right angles to the face of the plate and over the top edge of the plate 61. The arm 57, which is mounted on the extremity of the stud shaft 53, has an inwardly extending lug 72 which extends inwardly at right angles to the inner face of the arm and in the plane of the plate 62.

A weight 73 is formed on the plate 62 urging the plate normally in a counterclockwise direction, that is, until the lower edge 74 of the plate abuts a collar 75 integral with the stud shaft 63. This collar also acts as a stop for the plate 62 against further clockwise movement when the parts are in the position shown in Fig. 9.

To trace the cycle of operation of this device, reference may be made to Figs. 4 and 8 to 11 of the drawings.

The starting position is shown in Fig. 9. The plate 61 is urged anticlockwise by the spring 68, but its extension 66 strikes the ledge 71 on the plate 62, urging that plate clockwise. The clockwise movement of the plate 62 is limited by engagement of its extending arm 76 against the collar 75 on the shaft 63. Hence the two plates are held in fixed positions. In its fixed position, the plate 61 is disposed so that its upper pointed extension 65 is clear of the path of the arm 57, but the lower extension 64 is in that path.

When the toweling is drawn outward for making a fresh area available, the rollers 20 and 44 will be rotated, the latter in the direction to rotate the shaft 53 and the arm 57 anticlockwise in Figs. 8-11. During the early part of this movement, the arm 57 will engage the extension 64 on the plate 61, as shown in Fig. 10, and will rock the plate 61 clockwise, against the spring 68. As the plate 61 so moves, the extension 66 thereon will tend to move away from the lug 71 on the plate 62, and the plate 62 will move anticlockwise under the influence of its eccentric weight 73. The displacement of the plate 61 by the arm 57 is sufficient to permit the plate 62 to rock to the position of Fig. 11, wherein it stops by engaging the collar 75. When the arm 57 passes from the extension 64 of the plate 61, that plate has been displaced far enough so that its top extension 66 engages under the ledge 71 of the plate 62. This engagement limits further anticlockwise movement of the plate 61 by its spring 68, because such tends to rock the plate 62 further anticlockwise, which is prevented by the engagement of the end 74 against the collar 75. The two plates then stay in these positions.

When the arm 57 substantially completes a revolution, after setting the latch plates as aforesaid, it assumes the position of Fig. 8. Its ledge 72 comes into engagement with the projection 76 of the plate 62, and continued counterclockwise rotation of the arm 57 causes the plate 62 to be pivoted in the clockwise direction. As the plate 62 rotates in the clockwise direction, the ledge 71 slides off the top of the projection 66 and, in the preferred construction shown, at the same time it cams the latter downwardly a short distance so as to rock the plate 61 in the clockwise direction. When the ledge is freed from the extension 66, the spring 68 causes the extension 66 to engage the side of the ledge 71, as the spring constantly urges the plate 61 anticlockwise. However, the normally continued tension

on the toweling causes the arm 51 to continue anticlockwise, so that it engages the upper extension 65 of the plate 61 in a manner to be completely stopped. Preferably, the projection 76 of the plate 62 remains engaged by the arm 51 in the stopped position, but this is not essential where the stopping takes place after the plate 61 has moved clockwise to bring its top extension 66 to the side of the ledge 71.

When tension on the toweling, and hence torque on the arm 51, is released, the spring 68 will rock the plate 61 anticlockwise, restoring the parts to the position of Fig. 9.

From the foregoing description of the construction and operation of the mechanism, it will be understood that it fully accomplishes the purposes and has the advantages heretofore stated.

It should be understood that the mechanism, while having been described in detail, is not limited to specific construction beyond the scope of the appended claims.

What is claimed is:

1. In a dispensing device, a rotating member and mechanism to limit the rotation of said member to a predetermined angle, the mechanism including a base, a stop member movably mounted on the base, the member having a stop portion engageable by the rotating member to stop rotation thereof, means normally urging the stop member to position wherein its stop portion is out of the path of movement of the rotating member, means engageable by the rotating member at a predetermined point in its rotation, to displace the stop member into stopping position to dispose its stop portion in the path of the rotating member at a subsequent point in the rotation thereof, holding means to releasably hold the stop member in said stopping position, and means to release the holding means when the rotating member moves into engagement with the stopping means, whereby upon release of torque upon the rotating member, the stopping member may be moved to withdraw its stopping portion from the path of the rotating member.

2. In a dispensing device, a rotating member, a movable stop member having a stopping portion movable into the path of the rotating member to stop the latter, means operated by the rotating member to apply force to the stop member to displace it to a position wherein its stop portion is engaged by the rotating member at a subsequent point in its rotation, means to lock the stopping member in said locking position, means to release the locking means when the rotating member moves to stopped position, and means urging the stop member to position wherein its stopping portion is withdrawn from the path of the rotating member.

3. In a dispensing device, a rotating member, a movable stop member having a stopping portion movable into the path of the rotating member to stop the latter, means operated by the rotating member to apply force to the stop member to displace it to a position wherein its stop portion is engaged by the rotating member at a subsequent point in its rotation, means to lock the stopping member in said locking position, means to release the locking means including a release element engaged by the rotating member as it moves into stopped position, means urging the stopping member to a position wherein its stopping portion is withdrawn from the path of the rotating member, the release element being positioned to effect release only after the

rotating element is adjacent the stop portion of the stopping member, whereby the latter is not withdrawn until a stopping operation is effected, but may be withdrawn upon release of torque on the rotating member.

4. In a dispensing device, a rotating member, a base, a stopping member movably mounted on the base, the stopping member having two extensions movable into the path of the rotating member at angularly displaced points in the rotation, engagement of the first extension by the rotating member displacing the stopping member to position the second extension in the path of the rotating member, yieldable means urging the stopping member into position wherein the second extension is withdrawn from the said path, mechanism to lock the stopping member in its position wherein the second extension is in stopping position, said mechanism having release means operated when the rotating member moves into engagement with the stopping portion.

5. In a dispensing device, a rotating member, a base, a stopping member movably mounted on the base, the stopping member having two extensions movable into the path of the rotating member at angularly displaced points in the rotation, engagement of the first extension by the rotating member displacing the stopping member to position the second extension in the path of the rotating member, yieldable means urging the stopping member into position wherein the second extension is withdrawn from the said path, mechanism to lock the stopping member in its position wherein the second extension is in stopping position, said mechanism including a rockable member movable to interlock with the stopping member, a projection on the rockable member engageable by the rotating member as it moves into stopping position, to displace the rockable member from interlocking position, whereby upon release of torque upon the rotating member the yieldable means can displace the stopping member to position wherein the second extension is out of the path of the rotating member.

6. In a dispenser, a rotating member moved in the dispensing operation, a base, a pair of overlapping rockable members rockably mounted on the base, the first rockable member having two extensions movable into the path of the rotating member at different points in the path, yieldable means urging the first rockable member to position wherein its first extension is in the path of the rotating member and its second extension is outside said path, engagement of the rotating member with the first extension rockable member to stop the first rockable member to a position wherein the second extension is in the path of the rotating member, the second rockable member having a lock portion interengageable with the first rockable member, when the first rockable member is in stopping position, means urging the second rockable member to effect said interengagement when the first rockable member is in stopping position, the second rockable member having a projection moved into the path of the rotating member adjacent the second extension of the first rockable member, when the second rockable member is interengaged with the first, whereby the rotating member may effect the release of said interengagement when it moves to stopping position.

7. In a mechanism of the kind described, a base, a rotating member rotatable on the base

about a center, a rockable stop member and a rockable lock member, both mounted on the base for rocking about centers, the three centers forming a triangle, the stop member having two extensions engageable by the rotating member at different points in the rotation thereof, engagement of the first extension rocking the stop member to dispose the second extension in the path of the rotating member, yieldable means urging the stop member to a release position wherein the second extension is out of said path, the lock member having a lock portion overlapping the stop member when the stop member is in release position, means urging the lock member to rock oppositely to the rocking of the stop member by the yieldable means, said last-named urging means being weaker than the yieldable means, the lock portion of the lock member being moved into abutting relation with the stop member when the stop member is in stopping position, to lock the stop member therein, the abutment being to the side of a line between the centers of the rockable members toward the center of the rotatable member, the lock member having a projection extending into the path of the rotating member adjacent but in advance of the second extension of the stop member, whereby the rotating member acts to displace the lock member from abutting engagement with the stop member and is stopped by the latter.

8. In a dispenser for dispensing limited lengths of elongated material, a frame to receive a supply of material, a first roller mounted on the frame, and around which the material is rolled, the frame having a discharge outlet and a return inlet between which a quantity of material may extend for use, the discharge outlet being subsequent to said roller, a second roller subsequent to the inlet and across which the material is passed to a receiver, means connecting the rollers for rotation of the second when the first is rotated, means to limit the amount of rotation of one roller to fix the amount of material withdrawn at one time, means to direct the material from the supply against the first roller, including a movable guiding member, a support for said member pivoted to the casing, the support having first link means attached to the member, second link means pivoted to the frame and to the first

link means, said two link means being extensible to place the guiding member in guiding position and collapsible to withdraw the same, lock means on the frame to prevent collapse of the link means, and manually engageable means to release the lock means.

9. In a dispenser for dispensing limited lengths of elongated material, a frame to receive a supply of material, a first roller mounted on the frame, and around which the material is rolled, the frame having a discharge outlet and a return inlet between which a quantity of material may extend for use, the discharge outlet being subsequent to said roller, a second roller subsequent to the inlet and across which the material is passed to a receiver, means connecting the rollers for rotation of the second when the first is rotated, means to limit the amount of rotation of one roller to fix the amount of material withdrawn at one time, means to direct the material from the supply against the first roller, including a movable guiding member, a support for said member pivoted to the casing, the support having first link means attached to the member, second link means pivoted to the frame and to the first link means, said two link means being extensible to place the guiding member in guiding position and collapsible to withdraw the same, lock means on the frame to prevent collapse of the link means, and manually engageable means to release the lock means.
